UNITED STATES PATENT OFFICE

AUGUST F. WILLIAMS, OF CLEVELAND, OHIO, ASSIGNOR TO THE AMERICAN MULTIGRAPH COMPANY, OF CLEVELAND, OHIO, A CORPORATION OF OHIO

MEANS FOR PREVENTING SMUDGING IN PRINTING MACHINES

Application filed March 20, 1928. Serial No. 265,843.

This invention relates to a rotary printing machine, and particularly such machine equipped for printing addresses on envelopes, cards, etc. The machine is preferably of that type of addressing multigraph illustrated in Patents Nos. 1,625,256 and 1,627,240 issued to my assignee The American Multigraph Company.

In the operation of machines made in accordance with the patents mentioned, it has been found that sometimes the imprint on the envelope is imperfect, a certain smudging taking place. Experimenting with various means to cure this defect, I have discovered that the desired result can be accomplished by interposing a flexible shield between the address-carrying drum and the roller carrying the segmental platen. This shield stands normally well clear of the drum, so that there is no danger of the type on the drum inadvertently engaging an envelope on the far side of the shield. However, the shield has a sufficient opening to enable the printing of an address. This opening is preferably only 25 slightly longer than the maximum address lines on the plate and slightly shorter than the length of the platen. The plate is preferably thinner than the height of the printing lines above the address plate, and is so flexible, that it may be readily shoved forward by the platen. Thus as the platen begins to come into active position, it forces toward the drum the envelope as a whole, and the shield thus avoids any kinking of the envelope or bending it about a vertical line. The shield acts as a guide for the envelope being printed, and following the printing, the elasticity of the shield retracts it to normal position.

According to my theory, when the shield is inflexible and holds back the end portions of the envelope, the platen forcing the intermediate region of the envelope through the shield opening tends to bow the envelope in a longitudinal arc from one end of the platen to the other so that the intermediate region of the envelope instead of resting snugly against the platen is some distance in front of it and thus coats with the address plate without being properly backed by the

platen, resulting in an occasional smudging; while when the shield is very thin and flexible, it may be engaged by the platen and forced forward beyond the ends of the printing lines, and thus no bowing of the envelope takes place. Whether or not this be the reason for the result, extensive tests have demonstrated that this very flexible shield does prevent this smudging.

In the drawings, Fig. 1 is a vertical transverse section through an addressing multigraph equipped with my invention; Fig. 2 is an enlarged substantially horizontal section through the envelope platen and adjacent parts, as indicated by the line 2-2 on Fig. 1; Fig. 3 is a vertical transverse section of the machine on the plane indicated by the line 3-3 on Fig. 2 looking in the opposite direction from Fig. 1; Fig. 4 is an enlargement of a portion of Fig. 2, with the drum in printing position; Fig. 5 is an enlargement of the printing platen and shield shown in Fig. 1; Fig. 6 is an elevation of the envelope shield and adjacent parts, looking toward the platen; Fig. 7 is an elevation of the shield looking from the envelope pocket toward the printing drum and showing the address plate on the drum behind the shield, the ribbon being omitted; Fig. 8 is a cross-section through the shield, address plate and a portion of the envelope platen without the ribbon, as indicated by the line 8-8 on Fig. 7; Fig. 9 is a perspective of a portion of an address plate which may be employed in this machine.

I will first briefly describe the addressing multigraph as illustrated in Figs. 1, 2 and 3. For a fuller description reference should be had to the prior patents mentioned.

As shown in the drawings, the printing machine proper comprises a rotary drum 10, mounted on a shaft 11, journaled in end frame plates 12 and 13 above a roller platen 14 mounted on a shaft 15. Gearing 16 and 17 and a suitable coupling connect the drum and platen. Any suitable means is provided for rotating the drum and platen.

Mounted on the drum, may be means for printing the body of a form letter, as a blanket 20 (indicated conventionally in Fig. 1) 100

stretched about a segmental portion of the drum. The segment is shown as a semi-cylinder resting on the end members 28 and 29 of the drum and held in place by a spring hook 24 engaging the shaft 11. An inking ribbon 25 has its ends wound on spools 27 carried between the end members of the drum, such ribbon extending intermediately about the type form. It will be seen that in the construction described, when the drum is rotated, paper fed between the drum and platen may be printed by the characters through the ribbon.

The body of the drum adjacent one edge 15 of the segment 10 is shown in Fig. 1 as provided with a pair of longitudinal channels 30, 31 for the reception of the removable address plate. This plate may be of the form shown conventionally at 32 in Fig. 1, having 20 an arcuate intermediate region and depressed edge portions curled on themselves for strength, and adapted to occupy the channels 30 and 31 when it is shoved endwise into place. Between these channels is a portion 25 of the drum providing a support for the intermediate portion of the plate. The address plate, which is shown conventionally in Fig. 1, preferably has raised projections 35, Fig. 9, which carry embossed printing strips 30 36.

The address plates may be inserted manually or in other manner as desired, a different plate for each rotation. The paper may be fed manually or automatically as desired. 35 The drawing illustrates at 40 and 41 a pair of feed rolls connected by gearing 43 with the platen and operating to progress the paper to the region between the drum and the platen. The drawing also shows an ejector roll 45 40 geared with the drum and coacting with a stripper spring 46, but these parts are shown merely incidentally.

The mechanism described enables the simultaneous printing of the body and address 45 of an addressed letter through an inking ribbon with comparative rapidity. Mechanism which will now be described is provided to enable the envelope to be printed from the same address plate while in its same position 50 on the drum.

The envelope printing platen, designated 50 is a segment on a rotary member 51 adjacent the drum, at the rear thereof on an axis parallel therewith. This segment has such 55 arcuate extent as will coat with the address portion only of the address plate and not engage the salutation, should there be one on the plate. This platen 50 is normally idle but is arranged at the proper time to rotate 60 in cooperation with the address plate at the same peripheral speed. To this end, the platen roller 51 is made loose on a shaft 52, and driven by a gear 54 meshing with the gear 17 on the drum. This platen is connectible for rotation with the gear 17 on the

drum. This platen is connectible for rotation with the gear 54 by a single rotation clutch designated 60 as a whole.

The clutch is of the single rotation type and may be of the form shown in Fig. 2. That figure shows the gear 54 journalled on a stud 55 mounted in an extension of the end plate 13. One member of the clutch consists of a disk 60 rigid with this gear 54 and shown as pinned to a hub on the gear; another member consists of a disk 61 rigid with the platen; a third member comprises an intermediate disk 62 having radial ribs 63 occupying corresponding grooves in the disk 61 (after the manner of an Oldham coupling), and the final member comprises a locking pin 65 adapted to lock the members 60 and 62 together. This locking pin is slidably mounted in the member 60 and may engage a notch in the member 62. The clutch pin 65 is normally held withdrawn by a lever 80, which constitutes part of the detecting mechanism, which will now be described.

On the printing drum is a cam 70 (Fig. 3) which on each rotation of the drum acts on a roller 72 on the end of an arm 73 pivoted at 74 and having a depending portion 75 to which is anchored a tension spring 76. This arm has an overhanging lip 77 which bears against a compression spring 78, the other end of which bears against the arm 80 also pivoted at 74. The action of the cam accordingly is to raise the roller and swing the arm 80 toward the drum if the arm is free to move, otherwise to compress the spring 78.

The arm 80 is normally held in the position shown in Fig. 3, by a latch arm 90 which is a rock arm on a shaft 91 which carries another rock arm 92 constituting a detecting finger. Extending between the drum and envelope platen is a suitable pocket hereinafter described, for the envelope to be printed. The detector finger, when no envelope is present, extends through openings in the pocket as shown in Fig. 1, being held in that position by the light coiled spring 95 acting on the rock shaft 91. The finger in such position holds the latch arm 90 in the position shown in Fig. 1, to prevent the action of the arm 80. Whenever an envelope is placed in the pocket, it swings the detecting finger 92 downwardly and thus rocks the latch arm 90 free from the arm 80. Under these circumstances when the cam 70 acts on the roller 72, the arm 80 is moved toward the drum. This withdraws the arm from the clutch pin 65 and the spring 66 forces the clutch pin into action, thus locking the platen shaft 51 to the driving pinion 52 and giving the platen 50 one complete rotation to print the address on the envelope.

Before the printing of the envelope is completed, the cam 70 will have cleared the roller 72, and the arm 80 will have returned to the position of Fig. 1 where its beveled edge 81 130

will engage the collar 67 on the clutch pin and thus the clutch withdraws itself from action as the rotation is completed, stopping the driving of the platen 50.

I will now describe the pocket between the drum and envelope platen, in which the envelope is deposited by hand and out of which it is fed by the printing action. This pocket includes as its front member, my flexible shield heretofore mentioned.

As shown particularly in Figs. 1 and 5-8, the flexible shield 100 is a very thin steel plate standing in a nearly upright position, and secured at its lower end to a bottom bar 101. Adjacent its upper end the shield extends loosely across the rear of a cross rod 102, above which it projects freely to constitute the front guide into the pocket. The lower portion of the flexible shield is reinforced by a stiff metal plate 103 lying along its outer face. The same screws 104 may secure the shield and reinforcing plate to the bottom bar 101. The rear plate 105 of the pocket is secured at its lower end to this bottom bar 101, and above it has ears 106 embracing a cross rod 107; above that the rear plate curves over the top of the platen as shown at 108, and is finally anchored to a cross bar 109.

As shown in Figs. 6 and 7, the shield 100 has two upwardly projecting tongues 111 and 112 spaced apart to leave an opening 110 between them. The reinforcing plate 103 is located well below this opening 110. Registering holes 115 through the plate and shield provide for the passage of the detector finger 92. An opening 116 through a considerable portion of the rear plate 105 provides for the travel of the segmental platen 50.

While the opening 116 through the rear plate 105 is slightly longer than the segmental platen 50, the opening 110 through the shield is of less length than the platen as appears clearly in Figs. 6, 7 and 8. It results from this that the platen swings freely through the rear plate but coacts with the shield through the intermediate envelope and thus forces the envelope and shield together toward the printing drum. The opening 110 in the shield is longer than the lines 36 of embossed printing strips on the address plate, but the thickness of the shield is no greater than the height of these strips. Accordingly, in printing action, the embossed strips with the ribbon, project relatively through the opening 110 of the shield instead of the envelope being bowed through the opening to meet the address plate. Accordingly, there is no bending of the envelope by the ends of the platen.

So long as the shield is of no greater thickness than the projection of the printing characters of the address plate and is flexible enough so that the platen can readily force it forwardly, it will be effective to enable the envelope to come in printing coaction with

the type without bending the envelope transversely. As a matter of fact, I find a shield made of spring steel about seven thousandths of an inch in thickness is satisfactory.

The shield also prevents any contact of the ribbon with the portions of the envelope beyond the addressing region. I find that it is unnecessary to close the opening 110 above the platen path as the tongues 111 and 112 are effective in keeping the upper portion of the envelope from contacting with the drum.

In the operation of the machine, the envelope indicated at A in Fig. 5 is manually dropped into the pocket and rests on the bottom bar 101 and incidentally operates the detector finger 92. During the time the envelope is being placed, the segment 50 is well back of the pocket as shown in Fig. 1, but, when the envelope platen is clutched in, this segment forces the envelope and shield forward so that the address lines can act against the envelope through the inking ribbon 25 which overlies the address plate. The segmental platen and the address plate travel upwardly at the same peripheral speed and thus print the envelope by rolling contact and feed it upwardly, as indicated in Fig. 5.

If there were no front to the pocket, the envelope would be smudged by the travelling ribbon in advance of the address plate. On the other hand, when the front wall of the pocket is stationary, and has an opening through which the platen acts, the effect of the platen is to force the intermediate region of the paper through the opening in the shield, and experience shows that this action tends to bow forwardly the whole intermediate region of the envelope from one end of the platen to the other. With my thin flexible shield however, the bending of the end portions of the envelope is avoided and the smudging eliminated.

As the rubber segment goes out of coaction with the address plate after the address is printed on the envelope, the momentum of the envelope carries it over above the curved back plate 108, down which it travels by combined action of momentum and gravity and it is discharged beyond the anchorage 109.

I claim:—

1. The combination with a rotary printing couple, and a movable shield between them having an opening through which the printing impression is made, there being provision for moving said shield toward the printing member and retaining it there during the impressing action.

2. In a printing machine, the combination with a rotary printing couple, of an interposed shield having an opening through which the printing impression is effected, and means whereby said shield is moved by the platen and interposed envelope toward the printing member.

3. In a printing machine, the combination

with a rotary printing member and a cooperating rotary platen, of an interposed thin flexible shield having an opening through which the printing impression is effected, said shield being movable by the platen and interposed envelope toward the printing member.

4. The combination of a rotary printing member, a segmental form carried thereon, a segmental platen adapted to coact with the form, a thin flexible shield between the platen and form and having an opening through which the printing is effected and means whereby said shield is moved by the platen and interposed envelope toward the printing member.

5. The combination of a rotary printing couple, of a flexible shield located between them, and having an opening through which the printing is effected, the platen of the couple overhanging the ends of said opening.

6. The combination of a rotary printing couple, a flexible shield between them, having an opening through which the printing is effected, said shield being anchored adjacent its lower end, there being means for pressing the intermediate region of the shield toward the printing member of the couple during printing.

7. In a printing machine the combination of a rotary drum adapted to carry an address plate having projecting printing lines, a rotary segmental platen mounted on a parallel axis, a thin flexible shield lying between them and having an opening long enough so that the printing lines may pass through it and short enough so that the platen cannot pass through it.

8. The combination with a rotary printing couple, of a flexible shield extending between them anchored at its bottom and having an opening into which the printing form may project, the platen being longer than said opening.

9. The combination with a printing couple having a rotary drum adapted to carry an address plate and having a cooperating segmental platen, of a thin spring steel plate extending between the drum and platen and anchored at its lower edge and having an opening of less length than the segmental platen.

10. The combination with a rotary printing couple, of a flexible shield between them, means for anchoring the shield adjacent its bottom, and a stationary guide rod which the shield loosely engages at its upper portion, said shield having an opening through it beneath the guide rod.

11. The combination of a rotary drum, an address plate removably mounted thereon a segmental platen, a flexible shield between them anchored adjacent its bottom, and a stationary guide rod which the shield loosely engages at its upper portion on the side ad-

acent the drum, said shield having an opening through it beneath the guide rod, the platen extending at its ends beyond said opening.

12. The combination of a printing drum, a coacting segmental platen, a pocket between them adapted to sustain an envelope resting on its lower edge, said pocket having a rear plate with an opening through which the platen may travel, and having a flexible front plate adapted to be forced by the platen toward the printing drum.

13. In a printing machine, the combination of a rotary printing drum adapted to carry an address plate, a rotary segmental platen on an axis parallel with the printing drum, a substantially upright envelope pocket between the drum and platen, said pocket comprising a bottom bar, a rear plate secured thereto and having an opening through which the platen may move, and a flexible front plate secured to the bottom bar and having an opening through which the printing is effected, there being provision for moving the front plate toward the printing drum.

14. In an address printing machine, the combination with a printing member adapted to carry the form, a platen, an envelope pocket between them having an opening in one wall through which the platen may move, the other wall of the pocket comprising a flexible plate having an opening and a reinforcing plate below said opening.

15. In an address printing machine, the combination of a rotary printing drum, an address drum having projecting printing lines, an inking ribbon on the drum overlying the address plate, a platen adapted to coact with the address plate through the ribbon, an interposed shield between the platen and drum, there being provision for moving said shield with the material to be printed toward the drum as the printing impression is made.

16. In an address printing machine, the combination of a rotary drum, an address plate movably mounted thereon and having projecting printing lines, an inking ribbon on the drum overlying the address plate, a segmental platen on an axis parallel with the drum, a flexible shield between the drum and platen having an opening through which the printing lines and surmounting ribbon may project, the segmental platen being longer than the opening whereby it forces the material and shield toward the printing drum.

17. In an address printing machine, the combination of a rotary printing drum, an address plate removably carried thereon and having projecting printing lines, an inking ribbon on the drum overlying the address plate, a segmental platen at the rear of the drum on a parallel axis, a substantially upright envelope pocket between the drum and platen, said pocket having a rear wall with an opening through which the platen moves

and at its front wall having a thin flexible plate secured at its lower end and provided with an opening longer than the printing lines on the address plate and shorter than the segmental platen.

5 In testimony whereof, I hereunto affix my signature.

AUGUST F. WILLIAMS.
